US0D1108303S

(12) **United States Design Patent** (10) **Patent No.:** **US D1,108,303 S**
(45) **Date of Patent:** **** Jan. 6, 2026**

(54) **PIVOT LINK**

(71) Applicant: **HONEYWELL SAFETY PRODUCTS USA, INC.**, Charlotte, NC (US)

(72) Inventors: **Zheng Gu**, Shanghai (CN); **Peng Zhou**, Suzhou (CN); **Wenbo Wang**, Wuxi (CN); **Xiaojuan Zhu**, Suzhou (CN); **Ling Lin**, Shanghai (CN); **Lyndon Liu**, Shanghai (CN)

(73) Assignee: **Honeywell Safety Products USA, Inc.**, Latham, NY (US)

(**) Term: **15 Years**

(21) Appl. No.: **29/931,555**

(22) Filed: **Mar. 7, 2024**

Related U.S. Application Data

(63) Continuation of application No. 29/809,186, filed on Sep. 27, 2021, now Pat. No. Des. 1,022,792.

(57) **CLAIM**

The ornamental design for a pivot link as shown and described.

DESCRIPTION

FIG. 1 is a perspective view of a pivot link showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is an exploded perspective view thereof.

The broken lines illustrate features of the pivot link that form no part of the claimed design.

1 Claim, 6 Drawing Sheets
